AIRPLANE CONSTRUCTION

Halbert H. Holloway, Los Angeles, Calif.

Application June 2, 1932. Serial No. 614,885

5 Claims. (Cl. 244—30)

In the following specification, and the accompanying drawings, I shall disclose my invention, and certain preferred ways for utilizing it. I shall also mention certain of its more important objects. I do not limit myself to the forms of the invention disclosed, however, since various changes and adaptations may be made without departing from the essence of the invention as hereinafter claimed; and objects and advantages other than specifically mentioned, are included within its scope.

My invention relates particularly to transport airplanes, including, land planes, sea planes, and amphibians. Among its principal objects are; first, to greatly increase the safety of air transportation, by providing easy and safe descent means for the persons carried, independent of the flying structure; second, to provide means for very materially reducing the cost and time required for inspecting and servicing commercial airplanes; third, to provide generally improved airplane construction, and particularly improved means for attaching power units and cabin nacelles to flying structures; and, fourth, to accomplish the above stated objects by means of very simple, dependable, and inexpensive construction.

My objects are attained in the manner illustrated, more or less diagrammatically, in the accompanying drawings, in which:—

Figure 1 is a side elevation of a land plane that embodies my improved construction, certain portions being shown in longitudinal section taken on the line 1—1 of Fig. 2, and certain exterior portions being shown broken away to disclose interior features;

Figure 2 is a plan view of the construction shown in Fig. 1;

Figure 3 is a front elevation of the plane shown in Figs. 1 and 2, a portion thereof being shown in cross section taken on the line 3—3 of Fig. 2;

Figure 4 is a side elevation of the forward portion of an amphibian plane that embodies my improved construction;

Figure 5 is a front elevation of the plane shown in Fig. 4;

Figure 6 is an elevation in longitudinal section, of the upper portion of my improved construction, on an enlarged scale, presented for more clearly disclosing details thereof, the section being taken on the line 6—6 of Fig. 2;

Figure 7 is a plan view of the construction illustrated in Fig. 6, drawn to the same scale as the latter figure, the top skin of the plane wing having been removed in this view; and

Figure 8 is a plan view similar to that of Fig. 7, for the purpose of better illustrating the disposal of the parachute packs that are used with the cabin nacelles in my construction; and of one means whereby the parachutes may be automatically broken out at a predetermined interval after they have been discharged from the flying structure.

Similar reference numerals refer to similar parts throughout the several views.

Considering initially the first stated object of my invention, it is well known that passengers in air transportation cannot be depended upon to properly use individual parachute apparatus when an emergency arises. Many persons appear to completely lose control of their senses, and of the coordination of their muscles, under such circumstances; and even those who are not subject to this, may, by reason of their inexperience and lack of judgment, release their individual parachutes too soon, and thus become entangled with rear portions of the plane. To overcome this difficulty, I provide detachable nacelles for transporting passengers, which may be instantly released from the flying structure by the action of an operator. Such nacelles are provided with attached parachutes capable of supporting them, and their contained passengers, in such a manner that the descent will be easy and safe. I provide automatic means whereby these parachutes will be broken out at a predetermined time interval after the nacelles have been released; or be broken out automatically after the nacelles have left the flying structure by a safe distance. When thus broken out, the parachutes will support the nacelles with their contained passengers, and lower them to the ground at a low velocity in the well known way.

It will be seen at once that this method of lowering passengers in emergencies is much safer than the use of individual parachutes, since personal idiosyncrasies cannot play any possible part in the operation.

There is still another reason why the safety of passengers is increased when they are within such nacelles, which is that, whatever the shock of landing there may be, it is taken primarily by the nacelles, rather than by the individual passengers. Although the speed of descent may be slight, the descent may nevertheless occur when a strong wind is blowing. Parachutes, with their suspended loads, move laterally with respect to the ground at the same velocity as that of the wind that is blowing. It is not uncommon for the velocity of the wind at the ground

surface to be as much as 30 or 40 miles per hour. To land under these conditions is very much the same as getting out of an automobile that is running at that speed, and many persons 5 cannot accomplish this safely.

By the use of my invention, not only the shocks of descent in still air, but the shocks of landing in stiff breezes, are primarily taken by the nacelles, rather than by the passengers contained 10 therein. Ordinarily the passengers will remain strapped in their seats. The nacelles may, of course, be damaged by landing shocks, but the very fact that this is an intervening action, serves to prevent serious injury to the passengers. 15 Moreover, as will appear later, I prefer to construct my nacelles as completely enclosed containers. Therefore, if they should accidentally alight upon a lake, or other body of water, they will float, and the passengers will remain in safety 20 for an indefinite period without much discomfort.

Considering next the second stated object of my invention, it is well known that the cost and time required for inspecting and servicing commercial airplanes, is a serious, and relatively 25 great, item in the cost of operation. To secure safety, and to meet the requirements of the Department of Commerce, transport planes must be thoroughly inspected and overhauled at stated 30 flying intervals. This operation consumes many hours of time, and hitherto has required that the planes be laid up during these periods. For this reason, many air transportation companies maintain a number of extra planes, distributed 35 at strategic points along the route, and this frequently is absolutely essential where commercial flying schedules must be maintained. Such operating methods require a relatively large idle 40 investment in planes; and the flying time of each plane is much less than the elapsed time, by reason of the fact that it has to be laid up periodically, for inspection and service.

To improve these conditions, my invention provides quickly detachable and interchangeable 45 power units; comprising propulsion means, the necessary auxiliary apparatus, and the housing in which these are contained. These units are quickly separable from the flying structures. Thus, when an operating transport company 50 utilizes a fleet of identical planes, it need have only one or a few extra power units, located at strategic points. When one of the planes requires inspection and servicing, by reason of the 55 mileage that it has flown, it may have its power units quickly disconnected and replaced, by newly inspected and serviced power units, and thus remain in service a very large portion of the time.

There are many incidental advantages of this 60 possibility of my invention. Among these may be mentioned; the power units, when removed from the planes, are easier to inspect and repair than when they are in place; the inspection, instead of having to be done as quickly as possible, by use of many mechanics working feverishly for 65 short periods and remaining relatively idle for the intervening periods, may be accomplished by fewer mechanics working, not under high pressure and therefore more surely, for longer 70 periods; and the investment required for owning and operating the flying fleet as a whole, will be greatly reduced.

Passing now to a detailed description of my invention, and referring to the accompanying 75 drawings, I have selected for illustration of the

flying structure, an ordinary type of high wing monoplane, powered by two propulsion units, and having two detachable cabin nacelles adapted for containing six passengers each. In the case of the land plane depicted in Figs. 1, 2 and 3, 80 the landing gear and nacelles are adapted primarily for alighting on land. In the case of the specific variation illustrated, namely, the amphibian plane illustrated in Figs. 4 and 5, means are provided for alighting either on water or land. In any form in which my invention is contemplated to be used, the propulsion units and the cabin nacelles, except for the landing gear, are substantially identical. I have preferred, for the purposes of this disclosure, to show bi-motored planes, but the invention is perfectly adapted for use of planes having any number of motors. 85

In the drawings, the wings of the plane are shown at 11; and a fuselage intended primarily for carrying flying stresses only, is shown at 12. A central pilot's cockpit is shown at the leading edge of the wing, at 13; and the usual stabilizers, elevators, and rudder, are illustrated at the right hand end of the fuselage in Figs. 1 and 2. 90

Detachable power units are shown generally at 14. These are connected to the front spars 15 of the wings, preferably by means of three universal quick-detachable joints for each unit. For this purpose I prefer to use ball and socket 105 joints, admitting of some motion in any direction, and adapted to be tightly assembled without stresses other than the loads to be normally imposed thereon. Such joints are illustrated in section in Fig. 6, wherein the male elements 110 are shown at 16, surrounding ball extremities 17 of power unit frame members 18. One pair of the female elements of these joints is rigidly attached to the lower edge of front spar 15, spaced apart, in the manner indicated at 19. 115 The other female element 20 is located at the front edge of the wing, central with respect to the other two, and supported by means of four diagonal braces 21 attached to the forward surface of the front spar. The male and female 120 members of the attaching means may be in the form of flanged fittings as shown, and be assembled by bolts (and the use of shims where required); or these members may be screwed together, with or without interposed shims. 125

Frame members 18 lead downwardly to carry a suitable supporting structure for the propulsion means and auxiliary apparatus, said propulsion means being indicated externally by propellers 22 and cowls 23. The power unit frame also carries suitable forward landing gear, such as the pneumatic gears shown at 24 in Figs. 1 and 3; or the combined landing wheels 25 and pontoons 26 shown in Figs. 4 and 5. I prefer, and have shown, all the landing wheels as being retractable. 130 Thus, in Fig. 1, I have shown a long screw at 27, by means of which, in cooperation with the nut 28 and link 29, the landing gear may be retracted within the housing 30 of the power unit, to the position shown in dotted lines 31 of Fig. 1. 135

Such power units as have been described, may be easily detached from their planes within a few minutes, by breaking the three couplings 19 and 20.

It is common to have auxiliary apparatus adjacent the engines, and, in such cases, they also should be mounted upon the power unit frames. Controls leading from the engines can be carried into the pilot's cockpit through tubes 32 145 provided with means for disconnection, as indi- 150

cated at 33. These disconnecting means may be in the form of male and female heads, respectively carrying the terminals of the controls. In this manner, when a connector 33 is broken, it 5 will disconnect all of the controls at the same time; and, conversely, they will be connected up again when the connector is put back in place.

Housings 30 of the power units preferably butt 10 against the forward edge and lower surface of the wings; as indicated at 34 and 35; and they should be shaped to fit the wings closely at these points.

When a plane that embodies the described features of my construction needs servicing, it can 15 go to the hangar, have its forward end jacked up at the rear of the power unit, have the power unit disconnected and wheeled away for servicing, and have a new freshly serviced power 20 unit, of identical kind, installed. This whole operation need take only a few minutes, and the plane will then be ready for service again.

In my improved construction, I locate the passenger nacelles directly behind the power units. 25 Such nacelles are indicated generally at 36. They butt up against the power unit housings, and are so shaped and proportioned as to carry out the stream lining thereof; but they are not attached to the power units in any way, unless by vertically 30 slideable guides to limit possible side motion. The whole weight of the nacelles and their contents is suspended from the front and rear wing spars, or by brackets attached thereto, by quick-detachable means within the control of the pilot 35 or other official. The detachable means may consist of bayonet joints, such as are indicated most plainly in Fig. 6. As illustrated, these comprise socket members 37, rotatably mounted on the brackets attached to the front and rear wing spars 15 and 38 respectively. These socket members 40 may be rotated by levers 39, by means of cables 40 leading to the pilot's cockpit or other location convenient for the operator. These 45 sockets are constrained to remain in their normal supporting position, as by tension springs 41, until it is desired to release the nacelle. The nacelles are wholly supported by four rods 42, having pins 43 at their upper extremities adapted to 50 engage corresponding cam grooves 44 in the bayonet sockets 37. Obviously, with such an arrangement, when levers 39 are simultaneously operated, the whole nacelle will drop from the plane by reason of its weight. Whatever guides there may be cooperating with the power unit, 55 being merely to prevent sidewise displacement and being vertically slideable, will not interfere in any way with the dropping of the nacelle.

The nacelles preferably are of watertight construction, having forward bulkheads 45 and ceilings 46. Doors 47 in the forward bulkheads allow a steward or other official to enter for caring for the passengers in flight; and doors 48 permit ingress and egress of the passengers. Both doors, and the windows 49 of the nacelle, are constructed in such manner that they will be watertight when closed, so that the nacelle will float if it should fall on water. Seats for the passengers are indicated at 50, and ample space is provided at the rear of the passenger entrance, for 60 lavatory arrangements and the storage of hand baggage.

The nacelles described form no part of the flying structure, except that they are provided with rear landing wheels 51, for service under ordinary 65 conditions. After a nacelle has been dropped, the

plane can continue to fly as before, unless an emergency makes this impossible; but it will be deprived of its rear landing wheel under the nacelle, and will then have to depend upon some other means of contacting with the ground at the rear, such as an auxiliary tail skid 52.

Supported on the roof of each nacelle, and within the wing space between the spars, is a packed parachute 53. This is attached to the nacelle, and is adapted for supporting it in such manner as to make its descent velocity within the desired limit. When a nacelle is dropped, its parachute will drop with it, and some means must be provided for breaking out the parachute sufficiently far below the plane to insure that it will not foul therewith. I prefer to make this breaking-out means automatic, and a simple form of doing this is to have a coiled cord 54 resting upon the top of the parachute pack, and having one of its ends attached to the flying structure, as at 55. The other end of this cord is attached to the releasing mechanism of the parachute pack, as indicated at 56. Thus when the nacelle, with its 80 85 90 95 100 105 110 115 120 125 130 135 140 145 150 155 160 165 170 175 180 185 190 195 200 205 210 215 220 225 230 235 240 245 250 255 260 265 270 275 280 285 290 the operators will have the choice of entering a nacelle and dropping therewith, or of dropping the nacelles and afterward bailing out with their own individual parachutes.

5 There are many methods for utilizing variations of my invention that do not depart from its scope. Among these I would mention that, in the case of low wing planes the cabin nacelles may be expelled upwardly from the plane, instead of causing them to fall downwardly therefrom. This may be accomplished in various ways, as by projecting the nacelles by means of small charges of slow burning powder, or by sufficiently powerful compression springs that 15 may be quickly released. Other changes and adaptations will suggest themselves to those familiar with this art, and are contemplated by me as being within the scope of my invention.

Having thus apparently fully described my invention, I claim:

1. Airplane construction comprising; a flying structure; a power unit normally connected to said structure at three spaced points only, and quickly detachable from all portions thereof; a 25 quickly detachable cabin nacelle not enclosed by other structure, and that is normally connected to the flying structure independently of the power unit, immediately at the rear thereof; and means within the control of an operator for instantly 30 releasing the nacelle from said structure in any flying position.

2. Airplane construction comprising; a flying structure; a power unit including propulsion means, and housing therefor, normally connected 35 to said structure at three spaced points only, and quickly detachable from all portions thereof; a detachable and normally closed cabin nacelle that is not enclosed by other structure, and that is normally connected to the flying 40 structure independently of the power unit immediately at the rear thereof; and means within the control of an operator for instantly releasing the nacelle from said structure in any flying position; said nacelle being so dimensioned and proportioned as to complete the stream lines of the 45 power unit housing.

3. Airplane construction comprising; a flying

structure; a power unit including propulsion means, landing gear, and stream lined housing therefor, normally connected to the flying structure at three spaced points only, and quickly detachable from all portions thereof; a detachable and normally closed cabin nacelle suspended from the flying structure directly behind the power unit, not enclosed within other structure and so dimensioned and proportioned as to complete the stream lining of the power unit housing; 80 a parachute attached to the nacelle, normally supported thereby, and adapted to fall therewith; means within the control of an operator for instantly releasing the nacelle from said structure while in any flying position; and automatic means for breaking-out the parachute at 85 a pre-determined interval after the nacelle has been released.

4. Airplane construction comprising; a flying structure; a power unit including propulsion 95 means, a stream-lined housing therefor, and a forward portion of a sea-plane float, normally connected to the flying structure at three spaced points only, and quickly detachable from all portions thereof; a detachable cabin nacelle provided 100 with an after portion of a sea-plane float, not enclosed within other structure suspended from the flying structure directly behind the power unit, and so dimensioned and proportioned as to complete the stream lining of the power unit housing 105 and that of the forward portion of the sea-plane float; a parachute attached to the nacelle, normally supported thereby, and adapted to fall therewith; means within the control of an operator for instantly releasing the nacelle from said 110 structure while in any flying position, and automatic means for breaking-out the parachute at a predetermined interval after the nacelle has been released.

5. The construction set forth in claim 4 in 115 combination with a landing gear connected to the forward portion of said sea-plane float, and retractile therewith; the forward and after portions of said sea-plane float normally being so disposed as to form a hydro-plane step where 120 they abut.

HALBERT H. HOLLOWAY.
